UNITED STATES PATENT OFFICE.

ALBERT C. BELL, OF CHICAGO, ILLINOIS.

LOCK.

1,129,841.

Specification of Letters Patent. Patented Mar. 2, 1915.

Application filed May 21, 1910. Serial No. 562,610.

To all whom it may concern:

Be it known that I, ALBERT C. BELL, a citizen of the United States, residing at Chicago, in the county of Cook and State of Illinois, have invented a certain new and Improved Lock, of which the following is a full, clear, concise, and exact description, reference being had to the accompanying drawings, forming a part of this specification.

My invention relates to an improved lock construction adapted for use in connection with cases or boxes having hinged covers or locks for any purpose in connection with which a spring catch is carried by one member which when brought into operative relation with another member carrying the lock engages the mechanism of the lock to retain the two members together. By my construction the mechanism of the lock is much simplified and the cost of making the lock very much reduced without materially sacrificing effectiveness of operation.

The several drawings illustrating my invention are as follows:

Figure 1 is a back view of the lock with the catch in place, the back wall of the lock being removed to show the lock mechanism. Fig. 2 is a sectional view of the parts shown in Fig. 1 taken along the line 2—2. Fig. 3 is a horizontal sectional view through the cylinder of a modified form of the lock construction. Fig. 4 is a face view of the construction shown in Fig. 3. Fig. 5 is a view similar to Fig. 1 of a modified lock construction in which the cylinder is replaced by stops formed upon the lock casing. Fig. 6 is a view of the parts shown in Fig. 5 taken along the line 6—6. Fig. 7 is a view of a key adapted for use in connection with the construction shown in Figs. 5 and 6. Fig. 8 is a modified form of the construction shown in Figs. 5 and 6, in which the stops formed on the lock casing are replaced by projections carried by the lock tumblers.

Similar numerals refer to similar parts throughout the several views.

As shown in Figs. 1 and 2 the lock consists essentially of a casing 1 adapted to be

screwed to the inside of the box or receptacle 2 to be closed by the lock. The casing 1 has extending from its front face a tube 3 which contains a cylinder 4 which cylinder has near its inner end a section 5 of reduced diameter against which tumblers 6—6 normally rest under the action of a spring 7. The end of the cylinder 4 is made of smaller diameter than the portion 5 as shown at 8 to enter a suitable hole provided therefor in the back wall of the lock casing 1.

The tumblers 6 are not secured in any way to the casing 1 but rest loosely in the casing and are of such conformation that they cannot be displaced in the casing from their operative position being held in such position by the spring 7 which is also loosely contained in the casing around the tumblers 6 extending sufficiently above the cylinder 4 so as to hold such tumblers in proper position to be engaged by the catch 9 secured to the cover 10 when such catch is inserted through the opening in the top of the casing 1. It is to be noted that each tumbler is independent in its action and that therefore an attempt to pick the lock will be unsuccessful unless both tumblers are simultaneously engaged and moved to the position indicated in dotted lines which cannot be readily accomplished.

The lock is adapted to be opened by a key 11 which may be inserted through a slot provided therefor in the cylinder 4, the end of the key being conformed to span the portion 5 of the cylinder so that the ends of the key may engage the tumblers 6 to move them to the position indicated in dotted lines when the key is rotated for which position the catch 9 may be readily removed from the casing 1.

In the modification shown in Figs. 3 and 4, the cylinder 4 is replaced by a cylinder 4^a of such construction that no containing tube 3 is required since the cylinder is wholly contained within the casing proper of the lock, its ends being reduced in diameter to enter corresponding holes in the lock casing as indicated for the front or outer end of the cylinder in Fig. 4.

- In the modification shown in Figs. 5 and 6 the cylinder 4 is entirely omitted and projections 12 are formed from the casing to engage the tumblers 6 to hold them in proper position against the action of the spring 7 so that they may properly engage the catch when it is inserted in the lock casing and that they may be properly engaged by the end of the key shown in Fig. 7.
- 10 In the modification shown in Fig. 8 the tumblers 6^a are formed with projections 6^b which engage each other when the tumblers are in their normal position and thus serve to retain the tumblers in such position 15 against the action of the spring 7 as a result of which no projecting portions from the casing 1 of the lock are required. The key 11^a shown in Fig. 7 is adapted to operate the modified construction shown in Fig. 8 as well as that shown in Figs. 5 and 6.
- While I have shown my invention in the particular forms herein described, it is to be understood, however, that equivalent constructions may be employed without departing from the spirit of my invention.
- 25 What I claim is:
1. In a lock, the combination of a casing, tumblers inclosed loosely in such casing and unsecured thereto, such tumblers adapted to engage a catch insertible in the casing and to be engaged by a releasing key, and a separate spring for retaining the tumblers in engaging position.
  2. In a lock, the combination of a casing, tumblers inclosed loosely in such casing and unsecured thereto, such tumblers adapted to engage a catch insertible in the casing and to be engaged by a releasing key, and a separate spring loosely contained in the casing 40 to retain the tumblers in engaging position.
  3. In a lock, the combination of a casing, a tumbler inclosed loosely in such casing and unsecured thereto, such tumbler adapted to engage a catch insertible in the casing, and a separate spring for retaining the tumbler in engaging position, such tumbler adapted to be engaged by a key to remove it to a position disengaging the catch.
  4. In a lock, the combination of a casing, tumblers inclosed loosely in such casing and unsecured thereto, such tumblers adapted to engage a catch insertible in the casing and a separate spring loosely contained in the casing to retain the tumblers in engaging position, such tumblers adapted to be engaged by a key to be moved to a position disengaging the catch.
  5. In a lock, the combination of a casing, a tumbler having a hook formed thereon and loosely contained in the casing to rotate when operated, a catch adapted to enter the casing to engage the hook, and a

spring loosely contained in the casing separate from the tumbler tending to hold the 65 tumbler in engaging position.

6. In a lock, the combination of a casing, tumblers each having a hook formed thereon and loosely contained in the casing, a catch adapted to enter the casing to engage 70 the hooks, and a common spring loosely contained in the casing separate from the tumbler and tending to hold the tumblers in engaging position.

7. In a lock, the combination of a casing, 75 a tumbler having a hook formed thereon and loosely contained in the casing to rotate when operated, a catch adapted to enter the casing to engage the hook, a spring loosely contained in the casing separate from the 80 tumbler and tending to hold the tumbler in engaging position, and a device for opposing the action of the spring to hold the tumbler in operative position.

8. In a lock, the combination of a casing, 85 tumblers each having a hook formed thereon and loosely contained in the casing, a catch adapted to enter the casing to engage 90 the hook, a common spring loosely contained in the casing separate from the tumblers and tending to hold the tumblers in engaging position, and a device for opposing the action of the spring to hold the tumblers in operative position.

9. In a lock, the combination of a casing, 95 a tumbler having a hook formed thereon and loosely contained in the casing to rotate when operated, a catch adapted to enter the casing to engage the hook, a spring loosely contained in the casing separate from the 100 tumbler and tending to hold the tumbler in engaging position, and a cylinder adapted to limit the motion of the tumbler under the action of the spring and to receive a key for moving the tumbler to an inoperative 105 position.

10. In a lock, the combination of a casing, tumblers each having a hook formed thereon and loosely contained in the casing, a catch adapted to enter the casing to engage 110 the hook, a common spring loosely contained in the casing separate from the tumblers and tending to hold the tumblers in engaging position, and a cylinder adapted to limit the motion of the tumblers under the action 115 of the spring and to receive a key for moving the tumblers to an inoperative position.

11. A lock comprising only a casing, a loosely contained pair of tumblers each for directly engaging a catch and a key, and 120 a spring engaging the tumblers and tending to hold each tumbler in engaging position independently of the other tumbler.

12. A lock comprising only a casing, a loosely contained pair of oppositely disposed tumblers to be engaged by a key and 125

normally in the path of a coöperating catch, and a spring engaging the tumblers and tending to hold them individually in the path of said catch.

5 13. A lock comprising a casing, a pair of tumblers contained in the casing but unconnected therewith, a separate controlling spring for the tumblers, and stop mechanism for normally retaining the tumblers

against the action of such spring in position to engage a catch.

In witness whereof I hereunto subscribe my name this 17th day of May, A. D. 1910.
